C. MURRAY

DOUBLE FILAMENT VACUUM TUBE

Filed Aug. 7, 1923

Charles Murray Inventor

By

Robert A. Young Attorney

UNITED STATES PATENT OFFICE.

CHARLES MURRAY, OF WASHINGTON, DISTRICT OF COLUMBIA.

DOUBLE-FILAMENT VACUUM TUBE.

Application filed August 7, 1923. Serial No. 656,218.

To all whom it may concern:

Be it known that I, CHARLES MURRAY, a citizen of the United States, residing at Washington, District of Columbia, have invented certain new and useful Improvements in Double-Filament Vacuum Tubes, of which the following is a specification.

This invention relates in general to vacuum tubes and more particularly to an improvement in double filament vacuum tubes over the type disclosed in my pending application, Serial No. 632,128 filed April 14, 1923.

It is proposed to construct a vacuum tube having an outer glass container and a cylindrical plate, two filaments with a grid equidistant therebetween, being arranged in the circular plate.

The object of so placing the filaments on opposite sides of the grid electrode is to allow sufficient space between the filaments to prevent the filament not in use from becoming heated from absorption from the one being used.

Another object is that by such arrangement the same relative distance is accurately maintained between elements during the operation of either filament, and since the cold filament is always at zero potential, it is assumed the tube will operate as if no extra filament were contained in it, and no appreciable difference in working characteristics will be noticeable by changing the filaments.

With the foregoing and other objects in view, the invention consists in the combination of parts and in the details of construction hereinafter described and claimed; the specific embodiment being illustrated in the accompanying drawing which shows:

A vertical section through the vacuum tube showing the interior of the tube, the arrangement of the filaments in relation to the grid, and the various leads.

Referring more particularly to the drawing, a glass tube 1 is provided with an upper and lower base, 4 and 5 respectively. Interiorly the tube 1 is a cylindrical plate. A grid electrode, 13, and two filaments, 2 and 3, are placed within a cylindrical plate, 14, and are arranged equidistant from each other and the plate 14. The plate 14, grid 13, and filament 2, are provided with leads 14', 13', and 2', respectively, arranged with keepers, 6, and knife blade contacts 7, the leads passing through the lower insulated

base 5. The leads 3' from the filament, 3 pass through the upper insulated base and are provided with keepers 12, and knife-blade contacts 11. A suitable switch, 8, is arranged between the leads 3' and the leads 9 to the filament source of energy.

By arranging the filaments and grid in this manner the tube may be operated by shifting alternately from one filament to the other, allowing each in its turn to burn the same number of hours. In this way, the maximum efficiency and longevity of the filaments is assured.

The action which takes place within a vacuum tube during its operation is due to the electron flow which causes a wasting away of the filament, and the life of the tube depends entirely upon the length of time required to exhaust the filament.

By adding an extra filament, which may be done by merely throwing a switch, the life of the tube is lengthened over the life of a tube with one filament. The cost of such redesigning of the conventional tubes would be practically no more than the actual cost of the additional filament.

The additional feature of placing the grid between the two filaments and spacing them at equal distance from the grid, and the circular plate enclosing them, makes it possible to keep the inactive filament from becoming overheated from the active filament, and tend to keep the operation of the tube constant, and alike in working characteristics when either filament is brought into operation.

Claims:

1. In a radio oscillating tube, a cylindrical plate, a centrally disposed grid electrode, a plurality of independent energizing filaments, arranged on diametrically opposite sides of said grid electrode, and means for connecting said grid, plate, and filaments to external conductors.

2. In a radio oscillating tube, a cylindrical plate, a centrally disposed grid electrode, a plurality of independent energizing filaments arranged on diametrically opposite sides of and equidistant from said grid, and means for connecting said grid, plate, and filaments to external conductors.

3. In a radio oscillating tube, a cylindrical plate, a plurality of independent energizing filaments arranged interiorly of said plate, a grid located centrally between said filaments, the distances between the

grid and each filament and between each filament and the plate being equal, and means for connecting said grid, plate, and filaments to external conductors.

5. 4. In a radio oscillating tube, a cylindrical plate, a plurality of independent energizing filaments arranged interiorly of said plate, a grid located centrally between said filaments, an upper and lower base each

of which is provided with knife blade contacts and keepers, said plate, grid and one of said filaments being connected to suitable external conductors through said lower base, the other of said filaments being connected to suitable external conductors 15 through said upper base.

In testimony whereof I affix my signature.
CHARLES MURRAY.
